UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

AUTOMATIC FILLING-REPLENISHING LOOM.

Application filed February 23, 1924. Serial No. 694,505.

To all whom it may concern:

Be it known that I, ALONZO E. RHOADES, a citizen of the United States, and resident of Hopedale, county of Worcester, 5 and State of Massachusetts, have invented an Improvement in Automatic Filling-Replenishing Looms, of which the following description, in connection with the accompanying drawing, is a specification, like 10 characters on the drawing representing like parts.

This invention relates to automatic filling replenishing looms wherein a magazine or hopper containing a supply of fresh filling 15 carriers is provided and wherein upon the call for filling replenishment a fresh filling carrier is transferred from this magazine or hopper to the lay. It sometimes happens that the supply of filling carriers 20 in the magazine or hopper is allowed to run out. If this happens, or if for any other reason a fresh filling carrier is not in position in the hopper ready for transfer upon the call for filling replenishment, it 25 follows that when the call for replenishment occurs the mechanism will go through the operations of transfer but without transferring any fresh filling carrier from the magazine or hopper to the lay with the result 30 that one or more picks of imperfect weaving will occur before the loom is stopped.

It is the object of the present invention to provide a construction in which if, after 35 a fresh filling carrier has been transferred from the hopper to the lay, the supply of fresh filling carriers has become exhausted or for any other reason a fresh filling carrier is not brought into position ready for transfer that the loom shall then 40 be stopped, thus enabling the operative to fill up the hopper or properly to position the filling carriers therein so that a fresh filling carrier will be in position for the next transfer.

45 In my prior Patent No. 1,351,190, granted August 31, 1920, the desired object is secured by a mechanism in which the stopping of the loom is effected, when the condition referred to arises through the agency

of the protector mechanism commonly employed on looms of this type to effect the stopping of the loom in case the shuttle is not boxed properly or is trapped in the shed.

The object of the present invention is 55 to provide means for securing the desired object by preventing the shuttle from boxing properly and thereby rendering the protector mechanism operative to effect the actuation of the loom stopping means. 60

The object of the present invention is further to provide a means for securing the desired result which may readily be applied to existing looms and with little or 65 no alteration thereof.

The object of the invention is further to provide such a means which is delicate and sensitive in its action and requires very little power for its operation.

These and other objects and features of 70 the invention will appear more fully from the accompanying description and drawings and will be particularly pointed out in the claims.

The drawings show a preferred form of 75 the invention embodied in an automatic filling replenishing loom of the well known Northrop type provided with an ordinary form of protector mechanism.

In the drawings: 80
Fig. 1 is a side elevation partially in vertical cross section and partially broken away of a portion of the loom with a preferred form of the invention embodied therein.

Fig. 2 is a view in rear elevation of a portion of the mechanism shown in Fig. 1.

Fig. 3 is a top plan view of a portion of the mechanism shown in Fig. 2.

Fig. 4 is a detail in end elevation showing the knock off connections of the protector mechanism. 90

The general construction and operation of the Northrop type of automatic filling replenishing loom and the general construction and operation of the protector mechanism are both well known to those skilled in the art and hence it will be necessary 95

to describe only those features particularly related to the present invention.

The patent to Northrop, No. 911,152, granted February 2, 1909, illustrates the 5 ordinary form of protector mechanism.

In the loom illustrated for embodying a preferred form of the present invention, the breast beam 1 at the front of the loom supports at the right-hand side the hopper 10 stand 2 in which revolves the rotary hopper 3 carrying a supply of fresh filling carriers 4 arranged in a circular series of peripheral seats 5. This rotary hopper acts in the usual manner to bring the filling carriers 15 successively into transferring position which is the position occupied by the left-hand filling carrier 4 in Fig. 1. This position is usually determined by the butt of the filling carrier being brought by the rotation of the hopper into contact with a curved abutment 6.

When the running filling carrier has become wholly or partially exhausted suitable indicating mechanism sets in motion 25 mechanism by which replenishment is effected by a transfer of a fresh filling carrier from the hopper to the lay 7 and by which the exhausted filling carrier is forced out through the lay. This transfer is usually effected by a transerrer 8 pivoted upon 30 a stud 9 extending from the hopper stand 2. Upon the call for filling replenishment this transerrer swings downwardly forcing the filling carrier 4 against the abutment 6 out of the hopper onto the lay which is then located directly beneath.

It will be recognized that if a fresh filling carrier is not located beneath the transerrer or in position for transfer that 40 the transferring mechanism will go through its motions without effecting any transfer and the loom will continue to run with the exhausted filling carrier thus making one or more picks of imperfect cloth which it is highly desirable to avoid.

In the present invention whenever after transfer a fresh filling carrier is not brought into transferring position, or against the abutment 6, the mechanism at once acts to 50 stop the loom. So also, the loom may be stopped if a filling carrier is absent from any other predetermined position in the hopper as may be desired under particular circumstances. This stopping of the loom 55 in the present invention is effected through the usual protector mechanism and the operation of the protector mechanism is secured by preventing the proper boxing of the shuttle. The characteristic of the 60 protector mechanism is that it will act to stop the loom if the shuttle is trapped in the shed or in any other way prevented from boxing properly. In the present invention the proper boxing of the shuttle is prefer- 65 ably prevented by arresting the motion of

the usual picker stick so that the shuttle cannot box and this arresting action is determined by the absence of a fresh filling carrier from a predetermined position, such as the transfer position, in the hopper.

The construction and operation of an ordinary form of protector mechanism is fully disclosed in the patent of Northrop above referred to. In this type of mechanism when the shuttle 10 is properly and completely boxed at the end of its flight it presses rearwardly the movable shuttle binder 11 which is normally pressed toward the shuttle box. The shuttle binder when thus pressed rearwardly moves a binder finger 12 clamped on an arm 13 which projects from the dagger rod 14 journaled in suitable brackets 15 on the front of the lay. The binder finger when thus moved rocks the dagger rod 14 and raises the forwardly 85 projecting dagger 16 so that when the lay beats up with the shuttle properly positioned in its box the dagger will not engage the frog 17. If, however, the shuttle 10 is not properly boxed at the end of its flight or if it is trapped in the shed then the shuttle binder 11 will not be moved or will not be moved sufficiently to move the binder finger to elevate the dagger 16 to bring its path above the frog 17 consequently when the lay beats up with the improperly boxed shuttle, the dagger 16 will catch on the frog 17 and slide the frog forwardly. When the frog is thus slid forwardly its front end or bunter 18 contacts with the usual knock off lever 19 pivoted at 20 on the loom side and rocks the knock off lever causing it to throw the shipper handle 21 out of its retaining notch and allow it to spring to the end of its slot 22 and disconnect the driving power thus stopping loom, all in a familiar and well known manner.

In the present invention suitable means are provided for detecting a predetermined depletion of the supply of fresh filling carriers in the hopper or for detecting absence of a filling carrier from a predetermined position, such as the transferring position, in the hopper. For this purpose a bracket 23 is secured as by a set screw 24 to the transerrer stud 9 and depends therefrom. On this bracket is movably mounted, as by pivoting at 25, a feeler 26. In the form illustrated the upper end of this feeler normally stands adjacent the abutment 6 and is held in elevated position by a fresh filling carrier 4 when in position in the hopper ready for transfer. If the filling carrier is absent from this position then there is nothing to hold the feeler finger elevated and it will swing downward about its pivot 25.

A hook member comprising a long rearwardly extending rod 27 carrying a block 130

28 with a rearwardly bevelled lower face
29 and adjustably secured by a set screw
30 to the rod is pivotally mounted at 31 on
the bracket 23. This hook member is pre-
5 vented from being thrown too far upward-
ly by a stop 32 projecting from the bracket
23 and is normally held in elevated position
out of the path of the lay and a latch,
to be described, by a lug 33 projecting
10 laterally from the feeler finger 26.

In the preferred form of the invention
illustrated a bracket 34 is secured as by a
bolt 35 and a set screw 36 to the rear
15 of the lay 7 at the right-hand end. Upon
this bracket is movably mounted an arrest-
ing device which is movable into the path
of the usual picker stick 37 after it has
swung inwardly so as to arrest the opera-
20 tion of the picker stick and prevent the
shuttle from entering the box. In the con-
struction illustrated this arresting device
is shown as a rod or bar 38 carried by the
lower arm 39 of a lever having a hub 40
25 fulcrumed on a shaft 41 supported at its
ends in the bracket 34. A helical spring 42
secured at one end to the bracket and at
the other end to the hub 40 normally acts
to swing the lower arm 39 of the lever for-
wardly and thus to carry the bar 38 into
30 the path of the picker stick.

The arresting device is normally retained
in inactive position or in the position illus-
trated in the drawings by a latch. This
latch is shown as a bell crank lever ful-
35 crumed on a stud 43 projecting upwardly
from an arm 44 which projects rearwardly
from the bracket 34. The forwardly pro-
jecting arm 45 of this bell crank lever is
notched at its forward end to engage an arm
40 46 projecting upwardly from the hub 40
of the arresting device or lever. The later-
ally projecting arm 47 of this bell crank
lever extends beneath the path of the hook
device 27, 28. A helical spring 48 engaging
45 at one end the bracket 44 and at the other
end with the hub of the bell crank lever,
normally acts to swing the bell crank lever
so as to maintain the notched end of its arm
45 in engagement with the arm 46 of the
arresting device and thus retain the arrest-
ing device in its normal or inactive position.
A handle 49 projecting laterally from the
50 arm 46 of the arresting device enables the
arresting device to be swung into position
55 to engage the bell crank latch lever.

The operation of the mechanism will now
be apparent. So long as a filling carrier
4 is in place in the hopper in position for
transfer the feeler 26 is held in its normal
60 elevated position. The retaining latch lever
45, 47 holds the arresting lever against the
action of the spring 42 in its normal in-
active position with the bar 38 out of the
path of the picker stick 37. The feeler
65 finger 26 holds the hook member 27, 28 out

of the path of the latch. The parts are
then all in the position shown in the draw-
ings. If no filling carrier is in the transfer
position in the hopper, as for example when
replenishment takes place and no fresh fill-
70 ing carrier is brought into transfer position,
there is nothing to hold the feeler finger
26 elevated and it swings downwardly about
its pivot carrying with it the hook member
27, 28. The lower bevelled face 29 of the
75 block 28 allows the lay to beat forwardly,
if necessary, without disturbing the latch.
But upon the next rearward beat of the lay
after the dropping of the feeler 26 this block
28 of the hook member will catch behind the
80 arm 47 of the bell crank latch and swing it
out of retaining position and allow the
spring 42 to swing the arresting device to
carry the bar 38 into the path of the picker
stick which will then have swung inwardly.
85 Thus the picker stick is prevented from
swinging outwardly and as the shuttle comes
across the lay it strikes the picker stick and
is prevented from entering the box. Con-
sequently through the usual operation of the
90 protector mechanism the dagger 16 is left
in the path of the frog 17 and the shipper
21 is knocked off and the loom comes to a
stop.

When the loom has been stopped under the
action of the mechanism thus described the
operative then replenishes the hopper or
places the fresh filling carrier in position
in the hopper ready for transfer and resets
the mechanism. Consequently no operation
100 of the transferring mechanism can take place
without a fresh filling carrier actually be-
ing transferred.

The mechanism is readily adapted to ex-
isting looms because the bracket 23 is readily
placed in position on the end of the trans-
ferrer stud 9 and carries the feeler finger
and connected parts while the bracket 34 is
readily substituted for the usual bracket
105 at the end of the lay and carries the re-
mainder of the parts.

Having thus described the invention, what
is claimed as new, and desired to be secured
by Letters Patent, is:

1. An automatic filling replenishing loom
comprising a hopper containing a supply
of fresh filling carriers for successive trans-
fer to the lay, means for detecting a pre-
115 determined depletion of said supply, loom
stopping means, protector mechanism acting
to effect actuation of the loom stopping
means upon the failure of the shuttle to
box properly, and means controlled by the
detecting action of the detecting means
acting to prevent the shuttle from boxing
properly and thereby to render the protector
mechanism operative to effect the actuation
120 of the loom stopping means.

2. An automatic filling replenishing loom
comprising a hopper containing a supply
125

- of fresh filling carriers for successive transfer to the lay, means for detecting absence of a filling carrier from position ready for transfer upon the call for filling replenishment, loom stopping means, protector mechanism acting to effect actuation of the loom stopping means upon the failure of the shuttle to box properly, and means controlled by the detecting action of the detecting means acting to prevent the shuttle from boxing properly and thereby to render the protector mechanism operative to effect the actuation of the loom stopping means.
3. An automatic filling replenishing loom comprising a hopper containing a supply of fresh filling carriers for successive transfer to the lay, a movable feeler held against movement by the filling carrier when in position in the hopper for transfer to the lay and movable upon the absence of the filling carrier from said position, loom stopping means, protector mechanism acting to effect actuation of the loom stopping means upon the failure of the shuttle to box properly, and means controlled by the said movement of the feeler acting to prevent the shuttle from boxing properly and thereby to render the protector mechanism operative to effect the actuation of the loom stopping means.
4. An automatic filling replenishing loom comprising a hopper containing a supply of fresh filling carriers for successive transfer to the lay, means for detecting the absence of a fresh filling carrier from a predetermined position in the hopper, loom stopping means, protector mechanism acting to effect actuation of the loom stopping means upon the failure of the shuttle to box properly, a picker stick, an arresting device movable into the path of the picker stick to arrest the operation thereof, and means controlled by the detecting action of the detecting means acting to effect the movement of the arresting device into arresting position thereby to prevent the shuttle from boxing properly and thus render the protector mechanism operative to effect the actuation of the loom stopping means.
5. An automatic filling replenishing loom comprising a hopper containing a supply of fresh filling carriers for successive transfer to the lay, means for detecting the absence of a fresh filling carrier from a predetermined position in the hopper, loom stopping means, protector mechanism acting to effect actuation of the loom stopping means upon the failure of the shuttle to box properly, a picker stick, a movable arresting device normally tending to move into the path of the picker stick to arrest the operation thereof, means for retaining the arresting device out of arresting position, and means controlled by the detecting action of the detecting means acting to release the re-

taining means and thus permit the arresting device to move into arresting position thereby to prevent the shuttle from boxing properly and thus render the protector mechanism operative to effect the actuation 70 of the loom stopping means.

6. An automatic filling replenishing loom comprising a hopper containing a supply of fresh filling carriers for successive transfer to the lay, means for detecting the absence of a fresh filling carrier from a predetermined position in the hopper, loom stopping means, protector mechanism acting to effect actuation of the loom stopping means upon the failure of the shuttle to box 75 properly, a picker stick, an arresting lever fulcrumed on the lay, a spring normally acting to swing the arresting lever into a position to arrest the operation of the picker stick, a latch for retaining the arresting 80 lever in inactive position, and means controlled by the detecting action of the detecting means acting to release the latch and allow the spring to swing the arresting lever into arresting position thereby to prevent the shuttle from boxing properly and thus render the protector mechanism operative to effect the actuation of the loom 85 stopping means.

7. An automatic filling replenishing loom 90 comprising a hopper containing a supply of fresh filling carriers for successive transfer to the lay, a movable feeler held against movement by the filling carrier in position in the hopper for transfer to the lay, loom 100 stopping means, protector mechanism acting to effect actuation of the loom stopping means upon the failure of the shuttle to box properly, a picker stick, an arresting device mounted upon the lay and movable 105 into the path of the picker stick to arrest the operation thereof, a latch mounted on the lay for retaining the arresting device in inactive position, and a hook held by the movable feeler out of the path of the latch 110 during the movement of the lay but dropped in front of the latch upon the detecting movement of the feeler so that upon the next rearward beat of the lay the latch will be caught and tripped by the hook. 115

8. An automatic filling replenishing loom comprising a hopper containing a supply of fresh filling carriers for successive transfer to the lay, a feeler pivoted adjacent the hopper and held in elevated position by a filling carrier in position in the hopper for transfer to the lay, loom stopping means, protector mechanism acting to effect actuation of the loom stopping means upon the failure of the shuttle to box properly, a picker stick, an arresting lever fulcrumed on the lay, a spring normally acting to swing the arresting lever into position to arrest the picker stick, a latch pivoted on the lay and normally engaging the arrest- 120 125 130

ing lever to hold it in inactive position, a hook pivoted adjacent the feeler and supported by the feeler when in elevated position out of the path of the latch during the movement of the lay but dropped in the path of the latch upon the dropping of the feeler due to absence of the filling carrier

from transfer position so that upon the next rearward beat of the lay the latch will be caught and tripped by the hook. ¹⁰

In testimony whereof, I have signed my name to this specification.

ALONZO E. RHOADES.
